DESIGN FOR A COMBINED CALENDAR AND PENHOLDER

Henry Janssen, Wyomissing, Pa.

Application October 18, 1934, Serial No. 53,665

Term of patent 14 years

To all whom it may concern:

Be it known that I, Henry Janssen, a citizen of the United States of America, residing at Wyomissing, in the county of Berks and State of Pennsylvania, have invented a new, original, and ornamental Design for a Combined Calendar and Penholder, of which the following is a specification, reference being had to the accompanying drawings, forming part thereof.

Figure 1 is a perspective view of a combined calendar and penholder showing my new design;
Figure 2 is a plan view of the same;

Figure 3 is a front elevational view of the combined calendar and penholder, shown in Figure 1; and

Figure 4 is an end elevational view of the same.
I claim:

The ornamental design for a combined calendar and penholder as shown.

In testimony whereof I affix my signature.
HENRY JANSSEN.
